UNITED STATES PATENT OFFICE.

CHARLES F. ROBBINS, OF SOUTH WEYMOUTH, MASSACHUSETTS, ASSIGNOR TO
MARKEM MACHINE COMPANY, OF BOSTON, MASSACHUSETTS, A CORPORA-
TION OF MASSACHUSETTS.

MARKING-MACHINE.

1,365,062.

Specification of Letters Patent. Patented Jan. 11, 1921.

Application filed April 17, 1919. Serial No. 290,799.

To all whom it may concern:

Be it known that I, CHARLES F. ROBBINS, a citizen of the United States, residing at South Weymouth, county of Norfolk, State of Massachusetts, have invented an Improvement in Marking-Machines, of which the following description, in connection with the accompanying drawing, is a specification, like characters on the drawing representing like parts.

10 This invention relates to marking machines or printing machines of that type which involve a work-supporting platen on which the work is supported and a printing head movable toward and from the platen and carrying printing characters. One of the objects of the invention is to provide a marking machine of this type in which the movement of the printing head away from the platen is upwardly and rearwardly so that when the printing head is in its retracted position it is situated not only above, but to the rear of the platen.

Another object of the invention is to provide a novel means for supporting and operating the printing head by which the printing face will always be maintained in parallel relation with the platen in all positions of the printing head, and still another object of the invention is to provide a marking machine of this type having a yielding-sustained platen with means for automatically locking the platen from upward movement, and means to release the lock when the printing head is in printing position.

Other objects of the invention are to improve marking machines of this type, all as will be more fully hereinafter set forth.

40 In order to give an understanding of my invention, I have illustrated in the drawings a selected embodiment thereof which will now be described, after which the novel features will be pointed out in the appended claims.

In the drawings, Figure 1 is a vertical sectional view of a marking machine embodying my invention showing the printing head in printing position;

50 Fig. 2 is a section on the line 2—2, Fig. 1;

Fig. 3 is a view similar to Fig. 1 showing the printing head in its retracted position;

1 indicates a suitable frame which is de-

signed to be placed on a bench or table and which supports the operative parts of the machine. The work-supporting platen is shown at 2 and it is carried by a plunger 3 which is mounted for vertical movement in the frame and which is acted upon by a suitable spring 4 tending to hold it yieldingly in its elevated position. The printing head is shown generally at 5, and it is mounted for movement toward and from the platen 2, as usual in printing machines of this type. 65 The printing head may have any suitable construction, that herein shown being of the familiar type which includes a plurality of type disks 6, each having a plurality of type characters 7 thereon, and each being rotatably mounted in the head so as to bring any one of its type characters into printing position. This type of printing head is more or less commonly used in printing machines of this character. The printing head is 70 sustained on a supporting arm 8 which is mounted for movement upwardly and rearwardly from the position shown in Fig. 1 to that shown in Fig. 3. This movement of the arm is of such character that the printing face of the printing head will be always parallel with the platen in all positions of the arm. The supporting arm 8 is shown as pivotally connected at 11 and 12 to two rocking members 9 and 10 that are mounted 85 on two parallel shafts 13 and 14 that are carried in the frame 1. These rocking members 9 and 10 are also connected by links 15, said links being pivoted to the rocking members at 16 and 17, respectively. The rocking members 9 and 10, links 15 and arm 8 thus make a sort of parallel-ruler construction, and when the rocking members 9 and 10 are swung from the position shown in Fig. 1 to that shown in Fig. 3, the arm 8 will 90 be carried upwardly and rearwardly and during the entire extent of movement of the arm, it will be parallel to the positions shown in Figs. 1 and 3. The rocking members 9 and 10 may be given their rocking 95 movement by any suitable means. I have herein shown the member 9 as pivotally connected at 18 to a link or connecting rod 19 which in turn is pivotally connected to the crank pin 20 of a crank arm 21 carried by a 100 driving shaft 22. Hence at each rotation of the driving shaft, the printing head will

105

- be moved from its retracted position shown in Fig. 3 into its printing position shown in Fig. 1 and then back into its retracted position again. One advantage of this construction is that the retractive movement of the printing head is upwardly and rearwardly so that when the printing head is in its retracted position it is back of the platen and thus does not interfere at all with the operation of placing work on or removing it from the platen.
- 23 indicates an inking pad which is carried by supporting arms 24 that are hung from the frame 1. This inking pad is situated so that the type characters of the printing head will be brought into contact therewith when the printing head is at the extreme limit of its rearward movement, as shown in dotted lines Fig. 3.
- 20 The arms 24 are shown as pivotally hung on the frame 1 at 43, the upper ends of said arms being connected by a bridge portion 44. This bridge portion has a bolt or rod 45 screw-threaded thereto, which bolt extends loosely through an opening in a lug or ear 46 formed on the frame. 47 is a spring encircling said rod and situated between the lug or ear 46 and the head 48 at the end of the rod, said spring yieldingly holding the inking pad 23 in its proper position. A collar 49 adjustably mounted on the rod 45 limits the upward movement of the inking pad. When the type are brought into engagement with the inking pad the spring 47 permits said pad to yield downwardly slightly and then returns the pad to the position shown in the drawings. Thus a proper engagement of the type with the ink pad is always assured.
- 40 It will be noted that the rocking members 9 and 10 are so constructed and arranged that when they swing from the position shown in Fig. 1 to that shown in Fig. 3, the centers 11 and 12 will be carried to the rear of the pivotal shafts 13 and 14. When the centers 11 and 12 are directly over the shafts 13 and 14, the arm 8 will be in its highest or most elevated position, and the movement of the rocking members farther to the rear into the dotted line position, Fig. 3, will result in lowering the printing head. Hence the retracting movement of the printing head is first an upward and rearward movement and then a downward and rearward movement.
- 60 The driving shaft 22 is actuated by a suitable clutch device indicated generally at 25 which is constructed to bring the shaft to rest in the full line position Fig. 3 with the printing head slightly separated from the inking pad. When the machine is started the initial rotative movement of the driving shaft will swing the rocking members 9 and 10 into the dotted line position, Fig. 3, thus lowering the printing head into contact with

the inking pad 23, and continued rotative movement of the shaft will then move the printing head upwardly and forwardly from the inking pad, and then downwardly and forwardly to bring the printing head 70 into printing position shown in Fig. 1. The printing head will, therefore, always be freshly inked each time that the machine is set in operation.

As stated above, the platen 2 is yieldingly sustained on the spring 4 and the construction is such that the printing characters will be brought against the platen just before the position shown in Fig. 1 is reached so that the platen will be depressed slightly during each printing impression. I have provided herein means for locking the platen automatically in its depressed position each time that it is lowered and means for releasing the lock each time a 80 printing impression is made whereby different thicknesses of stock can be printed on without requiring any adjustment in the position of the platen.

The platen 2 has associated therewith 90 means for automatically locking it in depressed position and means are provided for releasing the lock each time the printing head is in printing position so that during the making of the printed impression 95 the platen is free to be moved upwardly by the spring 4, thus insuring a proper pressure of the type on the work.

The plunger or stem 3 has a collar 26 on its lower end to which is pivotally connected 100 one end of a link 27, the other end of said link being pivoted to a lever 28 that in turn is pivoted to the frame at 29. The rear end of this lever has a head 30 formed with a curved surface 31 that is concentric with the 105 axis 29. 32 indicates a locking lever which is pivoted to the frame at 33, said lever carrying at its end a locking roll 340 which is adapted to engage the surface 31. The construction of the locking lever 32 is such 110 that the roll 340 is situated above a line joining the centers 33 and 29 and, therefore, any tendency to move the friction surface 31 downwardly will result in locking the lever 28 from movement. The locking roll 115 340 permits the friction surface 31, however, to move upwardly freely. Downward movement of the platen 2 will swing the head 30 of the lever 28 upwardly, and hence the lock herein shown is such as to freely 120 permit the platen to move downwardly. The roll 340, however, co-operates with the friction surface 31 to lock the platen from upward movement. Means are provided whereby this lock is automatically released 125 each time that the printing head is carried into the position shown in Fig. 1 so that while the printing impression is being made the platen is free to be moved vertically. This releasing of the lock is herein provided 130

for by means of an arm 34 which is rigid with the locking lever 32 and extends upwardly therefrom and which is adapted to be engaged by a projection 35 carried by the 5 links 15 when the parts are in the position shown in Fig. 1. This projection 35 is shown as in the form of a bridge connecting the two levers 15 and as carrying an adjusting screw 36 that engages the upper end of 10 the arm 34.

Under some circumstances it is desirable to make the same printed impression on a plurality of pieces of sheet material, and when this is to be done, the various pieces 15 of sheet material may all be stacked up and the stack placed on the platen 2. When the machine is set in operation the printing head will be lowered into contact with the top piece of the stack and the movement of 20 the head will force the platen downwardly against the action of the spring 4 until the printing head has reached the lower limit of its movement, this downward movement of the platen being freely permitted by the 25 lock herein described.

As the printing head begins its return or retractive movement the lock becomes operative to hold the platen in its depressed position. While the printing head is retracted 30 the operator will remove the top sheet from the stack with the printed impression, and upon the next downward movement the printing head will make a printed impression on the sheet which is now exposed to 35 the top. As the printed impression is made, the lock is released so that the spring 4 acts to raise the platen an amount equal to the thickness of the sheet which has been removed, whereby a proper printing contact 40 will be provided between the printing head and the top sheet of the stack. Thus the successive sheets may be printed and removed as they are printed and the platen will 45 gradually move up under the influence of the spring 4 as the printed sheets are removed.

This construction also has the advantage that articles of different thicknesses may be successively printed without making any 50 adjustment of the platen to accommodate varying thicknesses, for at each printing impression the platen will be forced downwardly against the action of the spring 4

into a position corresponding to the thickness of the material being printed. 55

I claim:

1. In a marking machine, the combination with a frame, of a platen mounted thereon for vertical movement, a spring to resist downward movement of the platen, a lever 60 connected to said platen and having a friction locking face, a locking lever pivoted to the frame and having a roll engaging said friction face, a vertically-extending arm rigid with said lever, a printing head, ac- 65 tuating means therefor by which the printing head is moved toward and from the platen, and a projection carried by said actuating means and adapted to engage said arm when the printing head is in printing 70 position thereby to release the lock.

2. In a marking machine, the combination with a frame, of two rocking members pivoted thereto to turn about parallel axes, a supporting arm pivotally connected to the 75 ends of the rocking levers, a printing head carried by said arm, means to oscillate said rocking members from a position in which the pivotal connections between said members and said supporting arm and the axes 80 about which said members rock are in line to a position where the pivotal connections between said members and arm are above but back of said axes, a platen situated to be engaged by said head when the arm is 85 in the first-named position, and an inking pad situated to be engaged by said head when the arm is in the last-named position.

3. In a marking machine, the combination with a platen, of two lever members pivoted 90 intermediate of their ends to turn about parallel axes, a link connecting said lever members at one end, a supporting arm pivotally connected to said members at the other end, a printing head carried by said arm, and 95 means connected to one of said lever members and arranged to oscillate them from a horizontal position to a position slightly beyond a vertical position, and a platen with which the printing head engages when the 100 lever members are in their horizontal position.

In testimony whereof I have signed my name to this specification.

CHARLES F. ROBBINS.
